(57) **CLAIM**

The ornamental design for playground playcenter, as shown and described.

DESCRIPTION

FIG. 1 is a perspective view of a playground playcenter showing our new design;

FIG. 2 is a front elevational view thereof;

FIG. 3 is a back elevational view thereof;

FIG. 4 is a right side elevational view thereof;

FIG. 5 is left side elevational view thereof;

FIG. 6 is a top plan view thereof; and,

FIG. 7 is a bottom plan view thereof.

The broken line showing in the drawings is included for the purpose of illustrating portions of the playground playcenter and forms no part of the claimed design.
